US00D439851S

(12) **United States Design Patent** (10) Patent No.: **US D439,851 S**
Keeney (45) Date of Patent: ** Apr. 3, 2001

(54) **HAND-HELD COLOR MEASUREMENT INSTRUMENT**

GretagMacbeth, Spectrolino Spectrophotometer brochure, part No. 98.42.49 en, Mar. 1998.

(75) Inventor: **Richard A. Keeney**, Minneapolis, MN (US)

* cited by examiner

(73) Assignee: **Electronics for Imaging, Inc.**, Foster City, CA (US)

Primary Examiner—Antoine Duval Davis

(74) Attorney, Agent, or Firm—Barry R. Lipsitz

(**) Term: **14 Years**

(57) **CLAIM**

(21) Appl. No.: **29/120,892**

The ornamental design for a hand-held color measurement instrument, as shown and described.

(22) Filed: **Mar. 28, 2000**

DESCRIPTION

(51) LOC (7) Cl. **10-04**
(52) U.S. Cl. **D10/81; D10/78**
(58) Field of Search D10/78, 81, 46; 356/326.73, 402-422, 435, 434, 433, 432; 385/146

FIG. 1 is a top, front and right side perspective view of the hand-held color measurement instrument;
